(57) **CLAIM**

The ornamental design for a reciprocating shaver as shown and described.

DESCRIPTION

FIG. 1 is a front view of a reciprocating shaver showing the new design.

FIG. 2 is a rear view of the reciprocating shaver.

FIG. 3 is a left-side view of the reciprocating shaver.

FIG. 4 is a right-side view of the reciprocating shaver.

FIG. 5 is a top view of the reciprocating shaver.

FIG. 6 is a bottom view of the reciprocating shaver.

FIG. 7 is a front perspective view of the reciprocating shaver.

FIG. 8 is a rear perspective view of the reciprocating shaver; and,

FIG. 9 is a front perspective view of the reciprocating shaver, including a shaver cap.

The broken lines in the drawings depict portions of the reciprocating shaver that form no part of the claimed design.

1 Claim, 9 Drawing Sheets
